UNITED STATES PATENT OFFICE.

WILKS B. GREGG, OF CHICAGO, ILLINOIS.

GRAB BUCKET.

Application filed May 23, 1924. Serial No. 715,346.

To all whom it may concern:

Be it known that I, WILKS B. GREGG, a citizen of the United States, residing at Chicago, in the county of Cook and State of Illinois, have invented certain new and useful Improvements in a Grab Bucket, of which the following is a specification.

This invention relates to grab buckets or excavating devices of the clam shell or hinged jaw type and particularly to devices of this character which are intended for digging purposes such as excavating earth or handling heavy material.

The principal objectionable feature of the ordinary clam shell bucket is its inefficiency in digging when the lifting cable acts upon its closing mechanism. In other words, when the lifting cable starts to close the bucket it also has a tendency to raise the same so that the jaws are not forced into the material. One of the particular features of the present invention is the provision of suitable closing mechanism whereby by the action of the lifting or closing cable will have a comparatively strong tendency toward forcing the jaws into the material to be acted upon.

The objects of this invention are to provide an improved grab or excavating bucket; to provide a grab bucket having a novel form of closing mechanism whereby the strains on the closing cable will tend to force the jaws into the material; to provide a combined toggle and rope and pulley closing mechanism for a grab bucket; and, in general, to provide such an improved apparatus as will be described more fully hereinafter.

In the accompanying drawings illustrating this invention;

Figure 1 is a side view showing the bucket closed;

Figure 2 is a side view showing the bucket open;

Figure 3 is a sectional plan view taken on the line 3-3 of Figure 2;

Figure 4 is a front view;

Figure 5 is a sectional view taken on the line 5-5 of Figure 2;

Figure 6 is a front view of one of the scoops or jaws; and

Figure 7 is a sectional view taken on the line 7-7 of Figure 6.

In the particular form of the invention as shown in these drawings the bucket 10 is provided with two scoops or jaws 11 and

12 having coacting lips or digging portions 13 and 14. These lips are substantially U-shaped as shown in Figures 6 and 7 and have upwardly extending projections 15 for engagement with the sides of the bucket. 60 The longitudinal portions of the lips have downwardly extending tapered flanges 16 which are connected by webs or flanges 17 with the cutting edges 18. This construction enables the lips to be made very strong 65 while at the same time being comparatively light.

The jaw 11 has hinge arms 19 which are keyed or otherwise securely fastened to a cross shaft 20. This shaft is also provided 70 with a lever arm 21 which is keyed or otherwise securely fastened thereto.

The jaw 12 is provided with arms 22 which are pivoted on the shaft 20 and are connected together and also connected with 75 a lever arm 23, these arms forming a combined straddle lever or bifurcated lever as will be readily seen from Figure 5. The arrangement of the lever arms and jaws is such that the movement on the shaft or 80 pivot 20 is similar to the action of a pair of shears. The arm 21 has a bearing 24 at its outer end for sheaves 25 and 25'. The outer end is preferably provided with a cover or housing 26 for protecting the 85 sheaves. The arm 23 also has a bearing 27 at its outer end for sheaves 28 and 28' and has a housing 29 for protecting the same.

The shaft 20 is carried in bearings 30 in the lower end of side bars or frame members 31. These frame members are connected at the top by cross bolts or shafts 32, 33, 34, and a head casting 35 which forms a bail for supporting the other parts. Pairs of arms 36 and 37 are pivoted on the 90 respective shafts 32 and 33 and are provided at their upper ends with segmental gears 38 and 39 which engage with each other so that the arms must swing in unison. The outer ends of these arms are connected by pairs of links 40 and 41 to the outer sides or corners of the scoops 11 and 12 being pivoted thereto at 42 and 43. The respective pairs of arms and links are pivotally connected by cross shafts 44 and 45. 105 It will be seen that the respective pairs of arms comprise toggles which will give a powerful final closing movement.

The bucket opening or supporting cable arrangement will be readily understood 110

from Figures 1, 2 and 4. Two supporting members such as cables 46 and 47 each have one end connected with the outer edge of the scoop or jaw 11 and the opposite end connected with the outer edge of the scoop 12. The cable 46 passes under a sheave 48 on the shaft 32 and then up over a sheave 49 and down under a sheave 50 on the shaft 33 and then to the jaw 12. The cable 47 passes in a similar manner under a sheave 51, then up over a sheave 52 and down under a sheave 53 to the opposite side of the bucket. The sheaves 49 and 52 are carried on a shaft 54 which is also provided at the center with a supporting pulley 55. The sheaves 49 and 52 are also protected by housing members 56 and 57 which are carried by the shaft 54. The bucket supporting cable 58' may be fastened directly to the sheave 55 when a single line is to be used but if a double line is to be used the cable 58' may pass under the sheave 55 and up to the boom of the derrick or machine with which the bucket is to be used. The cables 46 and 47 are provided with stops 58 which are adapted to engage with stop plates or projections 59 on the head block 35 in order to limit the swinging movement of the jaws.

The bucket closing and lifting cable 60 extends from the boom or support (not shown) down under a sheave 61 on the shaft 34 then over and around sheave 28, then across and around a sheave 62 on the shaft 45, then back around the sheave 28', then across and around a second sheave 63, then up and over a sheave 64, then down and under sheave 25, then across and around a sheave 65 on the shaft 44, then back and around the sheave 25', then back and under a second sheave 66 on the shaft 44, and then up to a point of fastening 67 where it is becketed or secured to the head block 35. The sheave 64 is mounted in a bracket 68 on the side of the head block 35 and is arranged at a suitable angle so that the cable will be in proper alignment with the different sheaves which of course must be spaced and arranged in order to permit the line to cross without interference.

When the term cable is used it is intended to indicate any suitable flexible member such as rope, chain or the like which may be adapted for the purposes set forth.

When the bucket has been lowered to digging position, the tension on the lifting cable 60 is reduced so that the jaws are free to engage the material to be excavated. As the lifting cable is drawn up or tightened, it tends to draw the pulleys 25 and 28 together and consequently tends to swing the arms 21 and 23 upwardly thereby giving a powerful closing action to the jaws. At the same time it tends to draw the pulleys on the shafts 44 and 45 towards the center and consequently to press down on the links 40 and 41 there-

by augmenting the closing action. It will be noted that during the opening and closing movements the arms and links which are connected with the respective jaws are controlled by the coacting toothed segments so that they will work harmoniously. As the arms and toggles are drawn toward each other it will be seen that they have a toggle like closing action on the jaws which increases as the jaws approach each other, thereby giving a very effective final closing action. By means of this arrangement it will be seen that when power is applied to the lifting cable such power is utilized most effectively for closing the jaws instead of being reduced by the tendency to lift the jaws away from the material as occurs with most common forms of buckets. It will also be noted that the lid or reinforced cutting lips have a bridging action across the jaws which strengthens the edges so that they are not apt to be bent upwardly at the center as is common with the usual form of buckets.

When the bucket is to be opened for discharging, the holding or supporting cable 58 is drawn in or else the lifting cable 60 is slackened so that the bucket is supported by the cables 46 and 47. As the weight comes on these cables they lift up the outer edges of the jaws and swing them open as will be readily seen from Figure 2. As the lower stretches of these cables swing upwardly the cables are drawn at a sharp angle across their guiding sheaves which causes a cushioning action and prevents any undue jar when the jaws open to their fullest position or until the stops 58 engage with the abutments on the head piece. From this description it will be seen that I provide a bucket which will be particularly efficient in operation and which will utilize its own weight to a large extent in effecting the proper closing action as well as utilizing to the fullest extent the power applied thereto by the lifting or closing cable. Having thus described my invention, what I claim and desire to secure by Letters Patent is:

1. In a grab bucket, the combination of hinged jaws, flexible holding means engaging with the outer portions of the jaws, oppositely arranged arms coacting with the jaws, a supporting frame in which the jaws are pivotally mounted, sheaves mounted on said frame and on said arms and a lifting cable roved around said pulley and having one end secured to said frame, said cable tending to swing the arms toward each other when the bucket is to be closed.

2. In a grab bucket, the combination of a supporting frame, a pair of jaws pivotally mounted on said frame, arms connected with said jaws for swinging the same, oppositely disposed arms pivoted to the frame, interlocking gear segments secured to the upper ends of said arms, links between the outer

- ends of the arms and the outer portions of the jaws, sheaves mounted at the upper ends of the first named arms, sheaves mounted at the outer ends of the pivoted arms, and sheaves mounted on the frame, a cable co-acting with said sheaves and tending to draw the free ends of all of said arms inwardly when the bucket is to be closed, substantially as described.
- 10 3. A grab bucket comprising a head block having outwardly projecting side bars, jaws pivoted to said side bars, holding means connected to the outer portions of the jaws, upwardly projecting arms coacting with the respective jaws, sheaves mounted on said arms, levers pivotally mounted on the head block, gears secured to the upper ends of said levers and connected with each other, links connecting the outer ends of the levers with the outer portions of the jaws, sheaves mounted at the outer ends of said levers, guide sheaves on the head block, a cable roved around said various named sheaves and having one end connected with the head block, the arrangement being such that when a tension is placed on the cable for lifting the bucket it tends to swing the arms and levers inwardly to force the jaws together, substantially as described.
- 20 4. A grab bucket comprising a head block, side bars depending from said block, jaws pivoted at the lower end of said bars, a cross shaft above the block, a pair of sheaves mounted on said shaft, a pair of cables passing over said sheaves and having their ends connected to the outer portions of the bucket, guide rollers on the head block for said cables, a holding cable coacting with the shaft, a lifting cable for closing the bucket and means coacting with the lifting cable and the jaws of the bucket for swinging the jaws together.
- 30 5. In a bucket, the combination of a frame, jaws pivotally mounted on said frame, oppositely disposed levers pivoted to said frame, interlocking means for causing the levers to move together, links between the levers and the outer portions of the jaws, means tending to swing the free ends of the levers inwardly when the bucket is to be closed and means for supporting the bucket at the outer portions of the jaws for opening the same, substantially as described.
- 40 6. The combination with a grab bucket having two or more pivoted jaws, of toggles for each jaw adapted to be actuated by the lifting cable and tending to close the jaws of the bucket.
- 50 7. In a grab bucket, the combination of a supporting frame, a shaft mounted in said frame, a pair of hinge arms secured to said shaft, a jaw mounted on said arms, a lever arm also secured to the shaft, a second pair of hinge arms pivotally mounted on said shaft, a jaw secured to said arms, a lever arm connected with said last named hinge arms and means coacting with said lever arms and means for opening and closing the jaws.
- 60 8. In a grab bucket, the combination of a supporting cable, a cross shaft secured to said cable, sheaves on said cross shaft, a pair of cables passing over said sheaves, a frame, jaws pivotally connected to said frame and having their outer portions secured to the ends of said cables, guide wheels on said frame for said cables, upwardly and outwardly projecting arms coacting with said jaws, sheaves at the upper ends of said arms, levers pivoted to said frame, gears secured to the upper ends of the levers and engaging with each other to cause the levers to move simultaneously, links connecting the outer ends of the levers to the outer portions of the jaws, sheaves mounted at the upper ends of said links, guide sheaves on said frame, a cable for closing the jaws and lifting the bucket, said cable being roved around said sheaves and connected with the frame as hereinbefore described.
- 70 9. A digging lip for buckets, having a relatively sharp cutting edge and having longitudinal and transverse ribs on the lower side thereof.
- 80 10. The combination with a bucket jaw, of a substantially U-shaped lip having a transverse rib and a plurality of longitudinal ribs on the lower side thereof.
- 90 11. The combination with bucket jaws, of closing levers and closing toggles for each jaw and means coacting with both the levers and toggles to close the jaws.
- 100 12. The combination with a grab bucket, of cable jaw opening means, stops for regulating the opening movement, closing levers and closing toggles for each jaw coacting with said jaws and a cable for operating said levers and toggles for closing the jaws, substantially as described.
- 110 13. In an excavating bucket, the combination of a head block, arms secured to said head block and jaws pivotally connected to said arms.
- 115 14. In an excavating bucket, the combination of two or more pivoted jaws, a head block and means for supporting the head block at a fixed distance from the jaws.

WILKS B. GREGG.
